UNITED STATES PATENT OFFICE.

WILLARD W. SAWYER, OF NEW YORK, N. Y., ASSIGNOR TO THE SAWYER-BOSS MANUFACTURING COMPANY, OF SAME PLACE.

NUMBERING-MACHINE.

SPECIFICATION forming part of Letters Patent No. 617,052, dated January 3, 1899.

Application filed June 13, 1898. Serial No. 683,382. (No model.)

To all whom it may concern:

Be it known that I, WILLARD W. SAWYER, a citizen of the United States, residing at New York, (Brooklyn,) in the county of Kings and State of New York, have invented a certain new and useful Improvement in Numbering-Machines, of which the following is a specification, reference being had to the accompanying drawings.

10 This improvement relates to that class of numbering-machines in which revolving wheels set in a reciprocating yoke are employed; and the object of the invention is to provide a machine of this class in which the 15 numbers are imprinted closely together and yet be cheaply built, convenient in operation, and durable in use.

To these ends the invention consists in the peculiar construction, arrangement, and combination of parts hereinafter more particularly described and then definitely claimed at the end hereof.

In the accompanying drawings, Figure 1 is a front view of a numbering-machine constructed according to my improvement with part represented as broken away. Fig. 2 is an end view of the yoke and numbering-wheels detached from the frame. Fig. 3 is a perspective view of one of the wheels detached. Fig. 4 is a 30 similar view of a bearing-disk on which the type-wheel revolves. Fig. 5 is a similar view of a washer to be set between the disks. Fig. 6 shows a modified form of bearing for use without the washer.

35 Referring now to the details of the drawings by numerals, 1 indicates the frame, and 2 the yoke, both of the usual or any convenient form. Passing through this yoke are two pins 3, on which are supported the bearing-disks

40 4. In each of these disks is set a plug 5 and a spring 6, operating to force the said plug outward. Between the disks are set washers 7, which should be of such size as not to touch the wheel hereinafter described. Mounted on 45 each of these disks is an annular type-wheel 8, having on its outside the numerals from "0" to "9" and on the inner bearing-surface a series of recesses 10, in which engages the plug 5. Inside the outer rim of the wheel is formed 50 a flange 11, in which are cut ratchet-teeth 12 and a deep notch 13, which are engaged in the

usual manner by the spring-operated pawl 14, pivoted to arms 15, swinging on the upper pin 3.

The pins 3 project through the yoke and work in grooves 16 in the frame, so that these pins serve the threefold purpose of supporting the disks, acting as a guide for the yoke, and as a pivot for the arms 15.

If preferred, the separate washers may be dispensed with and the central part of the bearer made thicker to form a shoulder 4', as shown in Fig. 6. This shoulder I regard as an equivalent of the washer.

In the drawings I have for the sake of 65 spicuity left off some of the details of construction, because as nothing is claimed on these it is unnecessary to illustrate or describe them, the main features of the invention claimed being the peculiar form of wheel and 70 the method of mounting the wheel.

What I claim as new is—

1. In a numbering-machine, a numbering-wheel having a series of internal ratchet-teeth, and a bearing-surface of larger diameter than 75 said series of ratchet-teeth, substantially as described.

2. In a numbering-machine, a numbering-wheel having a recess to form a bearing-surface, and a flange inside of said surface provided with ratchet-teeth, substantially as described.

3. In a numbering-machine, the combination with the yoke, of pins passing through said yoke, bearing-disks mounted on said pins, 85 and type-wheels mounted on said disks and having ratchet-teeth projecting between the same, substantially as described.

4. In a numbering-machine, the combination of a frame having grooves in the sides, 90 with a yoke, type-wheels set within the yoke, a separate bearing-disk for each wheel, and pins passing through said yoke and disks and into grooves in the frame, substantially as described.

In testimony whereof I affix my signature, in the presence of two witnesses, this 8th day of June, 1898.

WILLARD W. SAWYER.

Witnesses:

THOS. E. ROBERTSON,
C. M. IRELAN.
